LAMP BULB FEEDING MECHANISM
 Edward F. Grgetic, Richmond Heights, Ohio, assignor to
 General Electric Company, a corporation of New York
 Filed Oct. 16, 1963, Ser. No. 316,632
 7 Claims. (Cl. 198—209)

This invention relates to apparatus for automatically feeding lamp bulbs in proper oriented position into the bulb-supporting head of a lamp making machine.

Present day high speed production manufacture of incandescent lamps requires the automatic feeding of the lamp bulbs into the work-supporting heads of the lamp sealing-in machine at a high rate of speed and in the same endwise oriented position. In the case of certain miniature type incandescent lamps which employ tubular glass bulbs of very small size, e.g., around $\frac{3}{8}$ inch outside diameter and one inch or so in length, the automatic bulb feeding mechanism must be adapted to support the bulb in a manner such as to leave most of its outer surface area exposed, during the feeding or transfer of the bulb into the bulb holder jaws of the sealing machine, in order to enable grasping and holding of the bulb by the said jaws. An additional reason for such requirement may be present in those cases where it is desired to apply an ink or other type lamp identification marking to the outer side of the lamp bulb while supported in the bulb feeding mechanism. The application of such a lamp marking to the bulbs may also require that the bulb be rotatably supported in the bulb feeding mechanism so that it can freely rotate therein during the application of the lamp marking around the cylindrical side wall of the bulb.

It is an object of the invention, therefore, to provide a novel bulb feeding mechanism simple in construction and effective in operation for feeding lamp bulbs at a high rate of speed into the bulb holders of an associated lamp-making machine.

Another object of the invention is to provide a lamp bulb feeding mechanism adapted to support individual bulbs for free rotation therein about their respective axes and to feed the bulbs in the same positional relation into the bulb holder jaws of an associated lamp-making machine with substantially the entire outer surface of the bulb exposed for ready grasping thereof by the bulb holder jaws.

Briefly stated, in accordance with one aspect of the invention, the lamp bulb feeding mechanism comprises an indexing carrier having a plurality of bulb-supporting arms each adapted to rotatably support a bulb in an upright open end down position resting thereon so as to be freely rotatable about its axis with a substantial portion of its outside surface area left exposed. According to a further aspect of the invention, the bulb-supporting arms are horizontally slidable on the carrier to effect withdrawal of the bulbs from bulb receiving pockets in the carrier and advance them into a predetermined bulb transfer position outward of the carrier so as to be substantially completely exposed for ready grasping and pick-up thereof by the bulb holder jaws of the lamp-making machine. In accordance with a still further aspect of the invention, the bulb-supporting arms are vertically movable so as to be disengageable from the bulb after the grasping thereof by the bulb holder jaws of the lamp-making machine and before return sliding movement of the arms to their original retracted position.

Further objects and advantages of the invention will appear from the following detailed description of a species thereof and from the accompanying drawings.

In the drawings, FIG. 1 is a plan view of lamp bulb feeding apparatus comprising the invention, a portion of

the bulb-supporting carrier thereof being shown broken away in order to illustrate the bulb-supporting means thereon.

FIG. 2 is a vertical section on the line 2—2 of FIG. 1.

FIG. 3 is a perspective view of the drive mechanism for the bulb-feeding apparatus.

FIG. 4 is an enlarged vertical section, partly in elevation, of the bulb escapement mechanism and one of the bulb-supporting heads on the associated bulb transfer turret of the bulb-feeding apparatus, and

FIG. 5 is an enlarged vertical section of one of the bulb-supporting heads on the bulb transfer turret of the apparatus.

Referring to the drawings, the bulb-feeding apparatus according to the invention comprises a horizontally disposed bulb transfer carrier or turret 1 provided at spaced points around its periphery with a plurality of heads 2 (eight in the particular case illustrated) for supporting and carrying glass lamp bulbs 3 in upright open end down position thereon and transferring them into the bulb-holding jaws 4 (FIG. 1) of an associated lamp-making or sealing machine 5. In the particular case shown, the glass lamp bulbs 3 are of generally tubular shape with a single open end 6 (FIG. 4), and they are of a comparatively small size, for example, around $\frac{3}{8}$ inch outside diameter and one inch or so in length. The turret 1 is mounted for rotative movement on a vertical center shaft 7 journaled in the stationary or bed portion (not shown) of the machine, and it is intermittently indexed about its rotative axis by suitable indexing means, as by a conventional electric motor-driven horizontal main drive or cam shaft 8 (FIG. 3) carrying a barrel cam 9 which successively engages with a plurality of rollers 10 depending from and disposed around the periphery of a circular index plate 11 fixed on the turret support shaft 7, to carry each head 2 progressively through a series of stations (eight in the case of the particular machine illustrated designated A to H).

The bulbs 3 are successively loaded, one at a time, into the heads 2 on the turret 1 at the main bulb-loading station A, or at the auxiliary bulb-loading station C, by an article feeding mechanism 12 which, in its general arrangement, is of the so-called vibratory bowl type commonly in use at present, similar to that disclosed in U.S. Patent 2,904,162, Simer, and comprising a circular hopper or bowl 13 for receiving a loose random collection of the bulbs 3. The bowl 13 is formed with a slightly frusto-conical floor and it is provided with one or more inclined feed tracks or ramps (two feed tracks 14 and 15 in the particular case illustrated) which extend upwardly from the floor of the bowl in a spiral manner around the inside periphery thereof. The bowl 13 is vibrated or oscillated about its vertical center axis, in an inclined arcuate path of movement corresponding approximately to the direction of inclination of the feed tracks 14, 15, by suitable vibrator mechanism (not shown) to thereby cause the bulbs 3 in the bowl 13 to move around the floor of the bowl generally outwardly thereof toward the side wall of the bowl and thence up the inclined feed tracks 14, 15 and into substantially horizontally extending respective discharge troughs 16, 17 which are fixedly mounted on the bowl so as to vibrate along therewith. The mechanism for vibrating the bowl 13 may be of any conventional type. According to a preferred form of such vibrating mechanism, however, the bowl 13 is supported on the upper ends of a plurality of inclined leaf springs which are arranged to impart the desired inclined arcuate oscillating movement to the bowl when they are alternately flexed by the downward pull of an electromagnet on the bowl and released by the de-energization of the electromagnet. The tubular bulbs

3 ride up the respective inclined tracks 14, 15 in single file and in endwise oriented position, i.e., disposed longitudinally of the feed tracks and either open or closed end first, and they are advanced into and through the respective troughs 16, 17 which, as shown, extend outwardly beyond the side of the bowl 13, from which troughs the bulbs are then discharged through respective apertures 18, 19 in the bottom thereof into respective underlying downwardly extending feed tubes 20 and 21. The bulb discharge apertures 18, 19 are of a size and shape (teardrop shape in the particular case shown) proportioned to the size of the tubular bulbs 3 being fed to cause them to overbalance and drop of their own weight, closed or heavy end first, into the said apertures and down through the feed tubes 20, 21. Any bulbs 3 that for any reason fail to drop into the apertures 18, 19 as they pass thereacross, simply continue to advance along the continuations of the feed troughs 16, 17 and are returned thereby back into the feeder bowl 13.

As shown in FIG. 2, the feed tubes or chutes 20 and 21 are provided with suitable bulb inverting means 24 for turning the tubular bulbs around end for end within the feed tube so as to be discharged in an open end down position from the lower ends of the feed tubes. To this end, the feed tubes 20 and 21 are formed of respective upper and lower sections 25, 26 and 27, 28 which are curved into merging relation to form respective substantially horizontally extending short intermediate sections 29 and 30 closed off at their ends by end walls 31 and 32, respectively. As the bulbs 3 slide closed end first down the curved upper sections 25 and 27 of the respective feed tubes 20, 21, they strike against the end walls 31 and 32 of the horizontal intermediate sections 29, 30 of the feed tubes and bounce back into and slide down the lower sections 26 and 28 of the feed tubes in an inverted open end first position. An air jet directed by respective nozzles 33 downwardly into the horizontally merged intermediate sections 29 and 30 of the feed tubes 20, 21, at the approximate momentary location of the trailing open end of the bulb at the instant of striking thereof against the end wall 31 or 32, assists and assures the proper tilting and redirection of the bulbs into the lower sections 26, 28 of the respective feed tubes 20, 21.

The vibrating bowl 12 is continuously operated at a rate such as to feed bulbs 3 into the feed tubes 20, 21 at a rate faster than the requirements of the transfer turret 2 so that a stack or reserve supply of bulbs 3 is caused to build up within the respective feed tubes 20, 21. Suitable control means are provided to interrupt the filling of the feed tubes 20, 21 with bulbs 3 when the stack or reserve supply of bulbs within the tubes attains or exceeds a predetermined level. The particular control means illustrated comprises respective air nozzles 34 (FIG. 2) for the feed tubes 20, 21 located on one side thereof and arranged to direct an air jet across the interior passageway thereof, through aligned openings in opposite sides of the tube wall, so as to impinge against the actuating vane 35 of, and thus actuate, respective electric circuit control switches 36 which are mounted on the other side of the respective feed tubes. The switches 36 control the operation of electrically operated air supply valves 37 which, in turn, control the supply of compressed air to nozzles 38 and 39 arranged to direct air jets horizontally across the underside of the respective feed troughs 16 and 17, immediately beneath the bulb discharge apertures 18, 19 therein, for the purpose of preventing the bulbs 3 from dropping through the said apertures and into the feed tubes 20, 21. When the stack or reserve supply of bulbs 3 in either of the feed tubes 20, 21 builds up to or exceeds the level where it blocks off the air jet of the respective nozzle 34, the respective switch 36 is then actuated to cause the air valve 37 controlled thereby to open, thus placing the respective air nozzle 38 or 39 in operation so as to interrupt the feeding or discharging of bulbs 3 into the respective feed

tube 20, 21 from the bulb supply troughs 16, 17 on the vibrating bowl 13. The operation of the air nozzle 38 or 39, and resultant interruption of the feeding of bulbs 3 into the respective feed tube 20 or 21, then continues until the stack or reserve supply of bulbs 3 in the feed tube drops below the level of the air jet from the nozzle 34, the unobstructed air jet then reactuating the switch 36 which then operates to close the air supply control valve 37 for the respective air nozzle 38 or 39. The resulting interruption of the air jet from the nozzle 38 or 39 then permits the advancing bulbs in the respective feed trough 16 or 17 to drop once again through the aperture 18 or 19 therein, thus reinitiating the feeding of bulbs 3 into the respective feed tubes 20 or 21. In this connection, the mere passage of a bulb across the air jet from nozzle 34, during the free fall of the bulb down the feed tube 20 or 21, does not interrupt the air jet long enough to actuate the respective switch 36 so as to cause initiation of the air jet from the respective nozzle 38 or 39 and resultant interruption of the feeding of bulbs into the respective feed tube 20 or 21.

The lower or discharge ends of the feed tubes 20 and 21 are located at the main and auxiliary bulb loading stations A and C, respectively of the turret 1 in positions directly over the heads 2 when at such stations so that the bulbs 3, on being released from the open lower ends of the feed tubes, drop directly into the underlying head 2. The feed tubes 20 and 21 are provided at their lower ends with conventional type escapement means 40 for holding back the stack of bulbs 3 in the tubes and releasing them therefrom one at a time into the underlying head 2. In addition, conventional type detector means (not shown) are provided at station B to detect whether or not a bulb 3 is present in the head 2 at said station (i.e., whether a bulb has been loaded into the head at the preceding main bulb loading station A) and if a bulb is missing from the head 2, to then actuate the escapement means 40 for the feed tube 21 at the auxiliary bulb loading station C when the empty head is subsequently indexed to and positioned at the said station C. The particular escapement means 40 shown for each feed tube 20, 21 comprises, in general, an upper spring-load bulb clamping shoes member 41 (FIG. 4) and a lower bulb retaining finger member 42 which are pivotally mounted by pivot pin 43 on the lower end of the respective feed tube 20 or 21 so as to be engageable with the second lowest and the lowermost bulbs, respectively, of the stack of bulbs in the feed tube to hold them in place therein. The two bulb-retaining members 41 and 42 are pivotally connected to, and actuated by a common operating link 44 in a manner such as to pivot one of the members into its bulb-holding position just before the other member is pivoted to its bulb-disengaging or releasing position. The operating link 44 is actuated by the movable plunger 45 of an electric solenoid 45 which is operated in proper time relation to the dwell of the heads 2 on the transfer turret 1 at the bulb loading stations A and C, as by the closure of a circuit control switch 46 for the solenoid by a cam 46' on the drive shaft 8.

The bulb-supporting heads 2 on turret 1 into which the bulbs 3 are loaded as they drop from the feed tubes 20 or 21 are comprised in part of bulb-receiving pockets 47 in the turret in the form of radially outwardly opening slots or notches spaced around the periphery of the turret into which pockets the bulbs 3 drop as they are released from the lower end of the feed tube, and in part of a plurality of substantially horizontally arranged bulb-supporting levers 48 corresponding to the respective bulb-receiving pockets 47 and pivotally mounted beneath the turret so as to extend generally radially thereof with their outer ends normally disposed directly beneath the respective bulb-receiving pockets in position to receive and support the bulbs 3 in rested open end down position thereon as they drop through the pockets from the

feed tubes 20, 21. The levers 48 are pivoted on respective slides 49 which are mounted on the underside of the turret 1 for sliding movement radially thereof within guideways 50 (FIG. 5) formed therein. The lever 48 of each head 2 underlies its respective slide 49 and it is pivoted thereon intermediate its ends on a pivot pin 51 for pivotal movement in a vertical plane extending parallel to the direction of sliding movement of the slide 49 on the turret. The lever 48 is spring-biased to its horizontal bulb-supporting position, as determined by the engagement of a stop pin 52 on the outer arm of the lever with the underside of the slide 49, by a compression coil spring 53 which is compressed between the inner arm of the lever 48 and the slide 49 and is held in place therebetween within respective wells 54 and 55 therein.

At its outermost end, the lever 48 of each head 2 is provided with a bulb-supporting roller 56 which is rotatably mounted on the upper end of the lever, on a vertical pivot shaft 57 carried thereby. The roller 56 is adapted to support the bulb 3 in an upright open end down position on the lever so as to be freely rotatably thereon about the axis of the bulb. The roller 56 is a diameter such as to closely fit and receive thereover the open end of the bulb 3 in order to effectively support and center the bulb in up-right position on the outer end of the lever, and it is provided at its bottom edge with a seating flange 58 on which the rim of the bulb is adapted to seat or rest. To permit ready placement or reception of the open end of the bulb thereover, the roller 56 is made of slightly frusto-conical or tapered shape with its narrower diameter at the top. The U-shaped notches or pockets 47 in the turret 1 are shaped to closely conform to the cylindrical outer surface of the tubular bulbs 3 in order to guide them, during the course of their free falling movement from the lower end of the feed tube 20 or 21, in proper centered position over the supporting rollers 56. Cooperating pairs of backing rollers 59, 60 are rotatably mounted on the underside of the turret 1 at the inner ends of the notches or pockets 47 therein to provide a roller cradle type backing support for the upper ends of the bulbs 3, when seated in position over the rollers 56 on levers 48, such as serves to hold the bulbs in upright position thereon and prevent them from tipping inwardly of the turret when pressure is applied to the sides of the bulbs in a direction radially inward of the turret. Tipping of the bulbs outwardly of the pockets 47 in the turret is prevented by a guard band 22 which, as shown in FIG. 1, extends around the periphery of the turret, closely adjacent thereto, from a point just before the bulb loading station A to a point just before the bulb unloading or transfer station G.

The slides 49 and the associated bulb-supporting levers 48 carried thereby are held in place within the respective guideways 50 by retainer plates 61 bolted or otherwise fastened to the underside of the guideway-forming members on the turret 1 so as to underlie the slides, and they are each provided with suitable friction means 62 for exerting a frictional force on the slide to restrain sliding movement thereof in its respective guideway 50. To this end, each slide 49 is provided with a spring retainer post 63 upstanding therefrom and extending upwardly through respective radially extending slots 64 in the turret 1 over which post a friction plate 65 is positioned so as to rest flat against the upper side of the turret and slide along with the slide 49 and post 63. The friction plate 65 is spring pressed downwardly into frictional sliding engagement with the upper side of the turret 1 by a compression coil spring 66 which is positioned over the post 63 and is compressed between the friction plate and a washer 67 positioned over the post and retained thereon by an adjustment nut 68 threaded on the post. In addition to pressing the friction plate 65 downwardly against the upper side of the turret 1 so as to have frictional sliding engagement therewith, the spring 66 also exerts an equal and opposite upward

force on the spring post 63 serving to press the slide 49 upwardly against the underside of the turret so as to likewise have frictional sliding engagement therewith. The friction plate 65 and slide 49 thus are, in effect, resiliently clamped against opposite sides of the turret 1 with equal and opposite pressures. To prevent foreign objects (dirt, broken glass, etc.) from accidentally dropping into the slots 64, the friction plates 65 are made of large enough size to completely cover the said slots at all times, i.e., in all positions of the slide 49 within its guide way 50.

The slide 49 and associated bulb-supporting lever 48 of each head 2 are normally located, and held by the friction means 62 in a retracted inner position radially inward of the turret 1, as shown in FIGS. 2 and 4, in which position the bulb seating roller 56 on the lever 48 is located directly beneath the corresponding pocket or notch 47 in the turret in position to receive thereover the open lower end of a bulb 3 as its drops from the feed tube 20 or 21 at one or the other of the bulb loading stations A and C, and supports the bulb in an upright position just clearing the two rollers 59, 60 which form the roller cradle backing support for the bulb. The slide 49 and associated lever 48 are maintained in the said retracted position at all times throughout the travel of the head 2 in its circular path of movement about the turret shaft 7 except at the bulb transfer or unloading station G and during its index to the next succeeding station H, at which time the slide 49 and associated lever 48 are moved radially outward of the turret to an advanced bulb-unloading outer position as shown in FIGS. 1 and 5 and then returned once again to their initial retracted position. While located at station D, the bulb 3 may have an identification marking applied thereto in a suitable manner as by means of a conventional type marking device 69 which, as shown in FIG. 1, may consist of a spring-biased inked marking pad 70 mounted on a pivoted supporting arm 71 which is arcuately oscillated by an actuating arm 72, during the dwell of the head 2 at station D, to press the inked marking pad 70 into engagement with and wipe it across the cylindrical outer surface of the bulb 3 tangentially thereto so as to impress an inked marking thereonto. The bulb being free to rotate about its axis because of its support on seating roller 56 and backing rollers 59, 60, it is therefore free to rotate along with the marking pad 70 as the latter wipes across the surface of the bulb in pressure contact therewith. During the subsequent index movement of the head 2 away from the bulb marking station D but before positioning of the next succeeding head 2 thereat, the marking pad 70 is returned by its support arm 71 to its initial retracted position to bring it into engagement with a reinking pad or roller (not shown) in readiness for the start of the next bulb-marking operation. The bulb 3 is maintained in proper upright position on its supporting lever 48 during the marking operation, and prevented from being tipped radially inward of the turret by the pressure applied against the bulb by the marking pad 70, by the backing support afforded by the rollers 59, 60 of the roller cradle within which the upper end of the bulb is seated.

From the marking station B, the heads 2 are successively indexed to stations E and F, which in the case of the particular apparatus illustrated are idle stations, and thence to the bulb transfer or unloading station G where the bulb-supporting lever 48 of the head 2 thereat is moved radially outward of the turret 1, by outward sliding movement of the slide 49 in its guideway 50, to its advanced outer position to carry the bulb on the lever 48 clear of the turret 1, i.e., out of the turret pockets 47, and into an advanced outer or bulb transfer position (FIGS. 1 and 5) between the bulb holder jaws 4 of an associated lamp-making apparatus such as a sealing machine, which jaws 4 then close against the bulb to grasp and hold it therebetween. The outward sliding movement of the slide 49 to carry the bulb 3 to its transfer

position is effected by the application of an actuating force to a thrust-receiving means on the lever 48 located below the pivot axis thereof, the particular thrust-receiving means shown comprising an operating arm 73 on the lever 48 depending therefrom at the region of its pivot axis and carrying a suitable thrust-receiving member 74 at its lower end such as a convex or ball-type roller 74 for application of the actuating force thereto. The actuating force is applied to the operating arm 73 of lever 48 by actuating means 75 comprising an actuating lever 76 having a bifurcated upper end 77 forming a channelway 78 into which the roller 74 passes and is snugly received as each head is indexed into the bulb unloading station G. As shown in FIG. 3 the actuating lever 76 is fastened on a pivot shaft 79 which is journaled in a stationary bracket portion 80 of the machine frame and is rotated by a lever arm 81 fastened at one end on the shaft 79 and connected at its other end by link 82 to one arm of a bell crank lever 83 pivotally mounted on the machine frame and carrying a cam follower roller 84 on its other arm which is engaged within the cam track (not shown) of a face cam 85 fastened on the main drive shaft 8 of the machine. During the dwell of each head 2 at the bulb transfer station G, the actuating lever 76 is operated to apply to the operating arm 73 of lever 48 first an outward actuating force, directed radially outward of the turret 1, to thereby effect the outward sliding movement of slide 49 and lever 48 to their outer advanced or bulb transfer position, and to then apply to the operating arm 73, after grasping of the bulb 3 by the jaws 4 of the associated lamp-making machine, an actuating force directed radially inward of the turret to effect first a downward tilting of the bulb-supporting lever 48 to withdraw the roller 56 thereon from within the bulb 3, and to then slide the lever 48 and slide 49 inwardly of the turret toward their initial retracted inner position. The downward tilting of the lever 48 to withdraw the bulb-supporting roller 56 thereon from within the bulb 3 before any inward sliding movement of the lever 48 and slide 49 to their retracted inner position is initiated, is necessary in order to prevent the bulb 3 from being broken or pulled out of the closed jaws 4 of the associated lamp-making machine by the bulb-supporting roller 56 during the inward sliding movement of the lever 48 and slide 49 to their retracted inner position. For this purpose, the bulb-supporting lever 48 is arranged for a limited amount of downward pivotal movement, against the force of biasing spring 53, to the tilted position shown in dash-dot lines in FIG. 5, as determined by the engagement of a stop screw 86 thereon with the underside of the slide 49, in which tilted position the bulb-supporting roller 56 is disengaged from and clear of the open lower end of the bulb 3 then held in the jaws 4 of the associated lamp-making machine. In addition, the frictional force exerted by the friction means 62 on slide 49, opposing sliding movement thereof relative to the turret 1, is so adjusted by the setting of the adjustment nut 68 controlling the compression of spring 66, as to be of greater magnitude than the minimum actuation force required to be applied by actuating lever 76 to the roller 74 on the operating arm 73 of lever 48 to effect the pivoting thereof to its tilted position against the force of its biasing spring 53. Thus, the inward force required against the roller 74 on the operating arm 73 of lever 48, to pivot or tilt it against the force of spring 53, is less than the inward force required against slide 49 to effect inward sliding movement thereof against the frictional force exerted on the slide by the friction means 62. As a result, the inward actuating force applied to the roller 74 on the operating arm 73 of lever 48, by the actuating lever 76 on its return inward stroke, acts to first pivot the lever 48 to its downward tilted position to withdraw the roller 56 thereon from within and disengage it from the bulb 3 held in the jaws 4 of the associated lamp-making machine, and

to then bodily shift or slide the associated lever 48 and slide 49 radially inward of the turret 1 toward their retracted inner position.

The tilting of the lever 48, and return of the slide 49 and lever 48 to their fully retracted inner position, by the inward throw of the actuating lever 76, may be effected entirely at the bulb transfer station G when the period of dwell of the heads 2 thereat is sufficient to permit such complete retraction. However, because of the inward movement required of the roller 74 in order to effect the tilting of the bulb-supporting lever 48, the total inward throw required for the actuating lever 76 to return the slide 49 and lever 48 to their fully retracted inner position will be greater than the outward throw required to move them outwardly to their advanced position. For such reason, if the speed of operation of the apparatus is such that insufficient dwell time exists, or if it should be preferable to limit the inward throw of the actuating lever 76 to correspond exactly to the outward throw thereof so that, on completion of its inward stroke it is in proper position to receive in its channelway 78 the roller 74 on the next succeeding head 2 as it indexes into station G, then in such case the additional inward movement of the roller 74 on the operating arm 73, to accomplish the complete return of the slide 49 and lever 48 to their fully retracted inner position, may be effected by a stationary cam track 87 (FIG. 3) onto which the roller 74 rides as the head 2 is indexed away from the bulb transfer station G. As shown, the cam track 87 is preferably spring-biased so as to be yieldable to the pressure of the roller 74 striking thereagainst on movement out of the channelway 78 in the actuating lever 76, during the index movement of the head 2 from stations G to H. This spring-biasing of the cam track 87 serves as a safety measure to prevent breakage of any of the parts of the head or the actuating mechanism therefor in the event any binding condition should develop therein for some reason. To this end, the cam track 87 is carried on a lever arm 88 pivotally mounted on the stationary bracket portion 80 of the machine frame and spring-biased, by compression coil spring 89, inwardly of the turret 1 against a limiting stop screw 90 fastened on the bracket 80. The engagement of the lever arm 88 with the stop screw 90, under the pressure of the biasing spring 89, fixes the cam track 87 in proper position to move the slide 49 and lever 48 inwardly of the turret into their proper retracted inner position, in readiness for the reception of another bulb 3 on the bulb-supporting roller 56 of the lever 48 during the next cycle of operation of the apparatus. Upon disengagement of the roller 74 from the cam track 87 during the course of index movement of the head 2 from stations G to H, the lever 48 is pivoted by the biasing spring 53 back to its normal horizontally disposed position, and during the ensuing travel of the head around the machine to the bulb transfer station G, the slide 49 and lever 48 are maintained and held in their retracted inner position by the frictional forces exerted by friction means 62 on the slide 49, against sliding movement thereof relative to the turret. By the construction and arrangement of parts as shown and described herein, a bulb feeding apparatus is provided which is not only effective to satisfactorily feed lamp bulbs one at a time at a high rate of speed, and with certainty on each index of the bulb transfer turret, into the bulb holder jaws of an associated lamp-making machine, but which is also adapted to feed the bulbs, even though of very small size, in a manner such as to leave substantially their entire outer surface exposed for ready grasping thereof by the bulb holder jaws of the lamp-making machine. In addition, the feeding mechanism is also constructed to support the bulbs for free rotation therein whereby to permit the application of a printed marking to the outer cylindrical surface of the bulbs by a simple wiping action of a printing pad tangentially across the bulb surface.

Although a preferred embodiment of our invention has been disclosed, it will be understood that the invention is not to be limited to the specific construction and arrangement of parts shown, but that they may be widely modified within the spirit and scope of the invention as defined by the appended claims.

What I claim as new and desire to secure by Letters Patent of the United States is:

1. Lamp bulb feeding apparatus comprising a turret provided around its periphery with a plurality of bulb-supporting heads, each of said heads comprising a slide mounted for horizontal sliding movement on said turret in a direction radially thereof, a bulb-supporting lever pivotally mounted on said slide for pivotal movement in a vertical plane parallel to the said direction of sliding movement of said slide, said lever extending generally radially outward of the turret from its pivot axis and adapted to support a bulb on its outer end, said lever being pivotable between a substantially horizontal bulb-supporting position and a downwardly tilted bulb disengaged position, spring means biasing said lever to its said horizontal bulb-supporting pivoted position, thrust receiving means on said lever located below the pivot axis thereof for application of an actuation force thereto in the direction of and acting to produce sliding movement of the slide on said turret, and cooperating friction means on said slide and turret exerting a frictional force on the slide opposing sliding movement thereto relative to the turret, said frictional force being greater than the minimum actuation force required against said thrust receiving means to pivot the lever against the force of said spring means.

2. Lamp bulb feeding apparatus comprising a turret provided around its periphery with a plurality of bulb-supporting heads, each of said heads comprising a slide mounted for horizontal sliding movement on said turret in a direction radially thereof, a bulb-supporting lever pivotally mounted intermediate its ends on said slide for pivotal movement in a vertical plane parallel to the said direction of sliding movement of said slide, said lever extending generally radially of the turret and adapted to support a bulb on its outer end, said slide and associated lever being slideable between a retracted bulb receiving position and an advanced bulb delivering position and said lever being pivotal on said slide between a substantially horizontal bulb-supporting position and a downwardly tilted bulb disengaged position, a compression coil spring compressed between said slide and the inner end of said lever to spring-bias the lever to its said horizontal bulb-supporting pivoted position, an operating arm on said lever depending therefrom at the region of its pivot axis and carrying a thrust receiving member for application of an actuation force thereto in the direction of sliding movement of said slide, and cooperating friction means on said slide and turret exerting a frictional force on the slide opposing sliding movement thereof relative to the turret, said frictional force being greater than the minimum actuation force required against said thrust receiving member to pivot the lever against the force of said spring means.

3. Lamp bulb feeding apparatus as specified in claim 2 wherein the said friction means comprises a friction plate carried by said slide and spring-pressed into frictional engagement with a flat friction surface on said turret.

4. Apparatus as specified in claim 1 and comprising, in addition, stop means on said lever engageable with said slide to limit pivotal movement of the lever between its said bulb-supporting and bulb disengaging positions.

5. Lamp bulb feeding apparatus comprising a turret provided around its periphery with a plurality of bulb-supporting heads, each of said heads comprising a slide mounted on the under side of said turret for horizontal

sliding movement thereon in a direction radially thereof, a bulb-supporting lever pivotally mounted on said slide for pivotal movement in a vertical plane parallel to the direction of sliding movement of said slide, said lever extending generally radially outward of the turret from its pivot axis and adapted to support a bulb on its outer end, stop means on said lever engageable with said slide to limit pivotal movement of the lever between a substantially horizontal bulb-supporting position and a downwardly tilted bulb disengaging position, said slide and associated lever being slideable radially of the turret between a retracted bulb-receiving inner position and an advanced bulb delivering outer position, spring means biasing said lever to its said horizontal bulb-supporting pivoted position, said turret having a plurality of radial slots extending vertically therethrough in alignment with respective ones of said slides, an upstanding spring retainer post fixed on said slide and extending upwardly through the respective one of said slots, a friction plate carried by said post and in surface engagement with a flat friction surface on the upper side of said turret, a compression coil spring compressed between a shoulder on said post and the upper side of said friction plate to spring press it into frictional engagement with the said friction surface so as to exert a frictional force on the slide opposing sliding movement thereof relative to the turret, and thrust-receiving means on said lever located below the pivot axis thereof for application of an actuation force thereto in the direction of sliding movement of the slide on the turret, said frictional force being greater than the minimum actuation force required against said thrust-receiving means to pivot the lever against the force of said spring means.

6. Lamp bulb feeding apparatus comprising a turret provided around its periphery with a plurality of bulb-supporting heads, index means including a cam shaft for intermittently indexing said turret to advance said heads successively through a plurality of stations including a bulb transfer station, each of said heads comprising a slide mounted on the under side of said turret for horizontal sliding movement in a direction radially thereof, a bulb-supporting lever pivotally mounted on said slide below said turret for pivotal movement in a vertical plane parallel to the said direction of sliding movement of said slide, said lever extending generally radially outward of the turret from its pivot axis and adapted to support on its outer end a bulb in upright open end down position, stop means on said lever engageable with said slide to limit pivotal movement of the lever between a substantially horizontal bulb-supporting position and a downwardly tilted bulb-disengaged position, said slide and associated lever being slideable radially of the turret between a retracted bulb receiving inner position and an advanced bulb transferring outer position, spring means biasing said lever to its said horizontal bulb-supporting pivoted position, cooperating friction means on said slide and turret exerting a frictional force on the slide opposing sliding movement thereof relative to the turret, an operating arm on said lever depending therefrom at the region of its pivot axis, and actuating means engaging with said operating arm when located at said transfer station and operated in proper time relation to the dwell of each head at said station to apply an actuation force to said arm in the direction of sliding movement of the slide on said turret, the said actuating force required against said operating arm by said actuating means to pivot said lever from its horizontal position to its downwardly tilted position being less than the said frictional force opposing the sliding movement of said slide relative to the turret.

7. Lamp bulb feeding apparatus comprising a turret provided around its periphery with a plurality of bulb-supporting heads, each of said heads comprising a bulb-supporting lever pivotally mounted on the under side

11

of the turret for pivotal movement in a vertical plane extending radially thereof, said lever extending generally radially outward of the turret from its pivot axis and having a bulb-centering roller rotatably mounted on its outer end over which the open end of the bulb is adapted to fit and rest to rotatably support and locate the bulb in open end down position thereon for rotation about its axis, and a pair of rollers rotatably mounted on the un-

12

der side of said turret for rotation about vertical axes and providing a roller cradle support against which the upper end of the bulb is adapted to seat to prevent movement thereof radially inward of the turret.
